UNITED STATES PATENT OFFICE

2,450,172

ACCESSORY STAND FOR CYLINDER TYPE
VACUUM CLEANERS

Paul E. Stoner, Jackson, Mich.

Application May 10, 1946, Serial No. 668,909

4 Claims. (Cl. 211—86)

1

The present invention relates to improvements in vacuum cleaners of the so-called cylinder type which in operation lies with its longitudinal axis in a horizontal position.

Vacuum cleaners of the above-described type are usually equipped with a large number of interchangeable tools which require frequent selection and change if an efficient cleaning operation is to be performed in a home, or other establishment. As these tools are bulky, as well as numerous, it is not practical to carry them upon the person while using the vacuum cleaner, nor are they well adapted to be neatly stored away with the vacuum cleaner when not in use.

According to the present invention a removable extension tool holder has been provided which may be mounted upon the cylinder portion of the cleaner on which the operating tools of the cleaner may be supported while the vacuum cleaner is out of use in storage, and at the same time is so designed as an operating part thereof that the tools may accompany the cleaner during the entire course of its operation.

Thus, one of the objects of this invention is to provide a cylinder type vacuum cleaner having an extension upon which the operating tools may be supported with the cleaner in service as well as in storage.

Another object of the invention is to provide an improved tool holder for vacuum cleaners of the type described.

A still further object of the invention is to provide a cylinder type vacuum cleaner having a tool holder removably attached thereto for holding the operating tools with the cleaner in service as well as in storage.

A still further object of the invention is to provide a saddle type tool holder for vacuum cleaners of the type described.

A still further object of the invention is to provide as a new combination a cylindrical type vacuum cleaner having an extension disposed centrally, longitudinally and vertically of its longitudinal axis for supporting the cleaning tools upon opposite sides of the extension, but adjacent a plane through the center of mass of the cleaner whereby the tools may accompany the cleaner in service.

These and other objects and advantages residing in the combination, construction and arrangement of the parts will be more fully appreciated from a consideration of the following specification and claims.

In the drawings,

Fig. 1 is a perspective view of the cleaner and

2

tool-holding extension as viewed from one side.

Fig. 2 is a view similar to Fig. 1 of the assembly as viewed from the opposite side,

Fig. 3 is a perspective view of the extension tool holder removed from the cleaner and viewed from one side, and

Fig. 4 is a view similar to Fig. 3 as viewed from the opposite side.

Reference character 10 generally indicates a 10 vacuum cleaner of the so-called cylinder type which may be equipped with runners 12, or other suitable carriage structure for supporting the cleaner as it is drawn over the floor by the operator exerting a pull upon the flexible hose 14 15 equipped with a tool receiving nozzle 16 upon one end, and a connection 18 at the opposite end insertable into the vacuum inlet 20 in a well known manner. Horizontally extending ribs 22 are shown provided upon opposite sides of the 20 generally cylindrical portions 24.

The extension tool holder comprises a suitable 25 saddle portion which in the illustrated form of the invention comprises a pair of forked members 26 having resilient arms 28 shaped to straddle the cylindrical portion 24 and formed at 30 to embrace the ribs 22. The arms 28 are shown spaced at 32 to provide clearance for the handle 34.

Vertically disposed and located centrally of and 30 along the longitudinal axis of the cleaner 10 is a mounting board 36, or equivalent structure, to which is connected a number of brackets 38, 40, 42 and 44, a number of resilient clips 46 and 48, as well as hooks 50, 52 and 54. It will be noted that the brackets, clips and hooks are all located 35 directly adjacent the central axis of the members 26 so that the center of mass of the extension tool holder will substantially coincide with the center of mass of the cleaner 10.

As shown in Figs. 1 and 2, the hooks 54 will 40 support the electrical extension cord 56 with the cleaner 10 in storage while the brackets 44 will support the hose 14 with the cleaner 10 in storage. The remaining tools 58, 60, 62, 64, 66, 68 and 70 are all adapted to be connected to the nozzle 16, interchangeably, and are repeatedly selected and interchanged with the cleaner 10 in service. It will be understood that the tools 58 to 70, inclusive, when not being used, will be supported in the manner indicated in Figs. 1 and 2, with the cleaner 10 45 in service, as well as in storage. By supporting the interchangeable tools directly adjacent the vertical plane through the center of mass of the cleaner 10, there is no tendency to cause the cleaner to upset or turn over while in service even 50 though the cleaner 10 is drawn over the floor 55

through a pull upon the hose 14 and without the operator exercising any particular care.

The extension tool holder is preferably detachably connected to the cleaner 10. This has been conveniently arranged in the illustrated form by having the members 28 formed from resilient material, such as spring metal, and engaging with the ribs 22 to prevent rotation of movement of the extension upon the cylindrical portion 24. Obviously, other forms for accomplishing the same results will appear to those skilled in the art.

Having thus described my invention, what I claim as new and desire to protect by Letters Patent is:

1. In combination with a cylindrical type vacuum cleaner having a horizontally extending casing, of an extension tool holder supported upon said casing having a vertically disposed tool supporting member extending longitudinally of said casing and disposed in a plane extending substantially through the center of mass of said casing.

2. In combination with a cylindrical type vacuum cleaner having a horizontally disposed casing, a tool holder comprising a saddle supported upon said casing and carrying a tool supporting member disposed longitudinally of said casing in a vertical plane extending substantially through the center of mass of said casing.

3. In combination with a cylindrical type vacuum cleaner having a horizontally disposed casing, a saddle comprising a pair of forked members engaging with said casing and spaced at points longitudinally thereof, said saddle carrying a vertically disposed tool supporting member, said member extending longitudinally of said casing and being disposed substantially in a vertical plane through the center of mass of said casing.

4. A tool holder for cylinder type vacuum cleaners having a horizontally disposed casing comprising a vertically disposed member having tool supporting means attached thereto on opposite sides, and an attachment saddle means in the

15 form of a pair of forked members longitudinally spaced and adapted to engage over the casing of the cleaner.

PAUL E. STONER.
